DISPENSING CAP

Robert N. Marona, Scarsdale, N.Y., assignor to General Foods Corporation, White Plains, N.Y., a corporation of Delaware

Filed Feb. 23, 1965, Ser. No. 83,918

Term of patent 14 years

(Cl. D58—26)

FIG. 1

FIG. 2

FIG. 3

FIG. 4

FIG. 1 is a front elevational view of a dispensing cap showing my new design;

FIG. 2 is a view in side elevation of said dispensing cap;

FIG. 3 is a view in perspective of said dispensing cap;

FIG. 4 is a top plan view of said dispensing cap.

The fragmentary broken line showing of a sealing tip and a container in FIGS. 1 and 2 is for illustrative purpose only.

I claim:

The ornamental design for a dispensing cap, substantially as shown and described.
